CLAIM

The ornamental design for a makeup brush cleaning box, as shown and described.

DESCRIPTION

FIG. 1 is a front, right and top perspective view of a makeup brush cleaning box showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the makeup brush cleaning box shown in alternate configuration in an environment of use; and,

FIG. 10 is an enlarged view of a portion of the makeup brush cleaning box shown within the area designated as 10 in FIG. 1.

The portions of the makeup brush cleaning box shown in broken lines in FIGS. 1-10 do not form part of the claimed design. The broken line showing of the makeup brush in FIG. 9 is for the purpose of illustrating portions of the environmental structure and forms no part of the claimed design.

The dot-dash broken lines encircling portions of the makeup brush cleaning box in FIG. 1 and illustrated in the enlarged view in FIG. 10 form no part of the claimed design.
